LOOSE LEAF BINDER

Paul O. Unger, Glen Ellyn, Ill., assignor to Wilson-Jones Company, Chicago, Ill., a corporation of Massachusetts

Application June 22, 1933, Serial No. 676,994

13 Claims. (Cl. 129—1)

This invention relates to a loose leaf binder, and more particularly to a label holder for the same.

It is an object of this invention to provide a label holder that may be manufactured inexpensively and applied to a loose leaf binder with a minimum of time and labor. It is a further object of this invention to provide a label holder that will remain in place throughout the life of the binder and will not scratch or mar any surface with which it may come in contact. It is a further object of this invention to provide a label holder that will enhance the appearance of the loose leaf binder to which it is attached. Other objects of this invention will become apparent upon reading the following description taken in conjunction with the accompanying drawing in which:

Figure 1 is a fragmentary perspective view of a loose leaf binder embodying the invention;

Figure 2 is a cross section on the line II—II of Figure 1 with conventional parts broken away;

Figure 3 is a longitudinal section on the line III—III of Figure 1;

Figure 4 is a view similar to Figure 1 showing a modified embodiment of the invention;

Figure 5 is a cross section on the line V—V of Figure 4 with conventional parts broken away; and

Figure 6 is a longitudinal section on the line VI—VI of Figure 4.

In the drawing, the reference numerals 2 and 3 indicate a pair of covers connected to a back member 4 by means of hinges 5, 6 of any suitable construction. The back member consists of a back plate 7 and a hinge plate 8. The back plate 7 has a plurality of tongues 9 struck therefrom and projecting through slots (not shown) in the hinge plate 8. The tongues 9 engage a conventional ring metal 10 to hold the ring metal and the sheets 11 in the binder. The back 7 is provided with a covering 12 of leather or suitable fabric to match the binding on the covers 2 and 3. The edges of the plate 8 are curled to form hinge barrels for the hinges 5 and 6.

The label holder illustrated in Figures 1, 2 and 3 consists of a sheet 13 of celluloid or similar material having a pair of flanges 14 embracing the edges of the back plate 7. The sheet 13 is preferably of resilient material so that the flanges may be positioned by snapping the flanges over the edge of the back plate. The tongues 9 clamp the back plate 7 and the hinge

plate 8 together with the flanges 14 of the label holder therebetween.

The sheet 13 is provided with an embossed portion 15 defined by a pair of parallel raised walls 16 connected at one end by a raised wall 17 and at the other end by a curved slot 18. The slot 18 is shaped so as to provide an integral tab 19 depending between the walls 16 of the embossed portion 15.

Referring to Figure 3, it will be seen that a label 20 inserted through the slot 18 into the space defined by the embossed portion 15 will have its top edge lying against the tab 19. The tab 19 may be bent slightly so that it will press against the label 20 to prevent dislodgment of the label in case the binder is turned upside down. The tab 19 also acts as a guide to facilitate removal of the label 20 from the label holder. It is obvious that the tab 19 may be of any desired shape. It is essential, however, in order to attain the full advantages of the invention, to have the free end of the tab 19 depend below the upper extremities of the embossed portion 15 so that the end of the label 20 is accessible for removal. If the slot 18 is straight it is generally rather difficult to remove the label from the holder.

If desired, a sheet 21 of foil or other thin material bearing a suitable decorative design may be positioned adjacent the back plate 7 and held in place by the sheet 13 of transparent material. The label 20 is then received between the transparent sheet and the decorative sheet. This arrangement makes it possible to achieve beautiful and unusual decorative effects.

The binder structure illustrated in Figures 4, 5 and 6 is the same as that previously described except for the construction of the label holder. Accordingly, the binder structure is designated by the same reference characters, and only the label holder structure will be described in detail.

The modified form of label holder consists of a sheet 22 of any suitable material such as celluloid, impregnated paper, or sheet metal. It is preferable to use resilient material for the sheet 22, but many of the advantages of my construction may be attained even with the use of non-resilient material. The sheet 22 is provided with a pair of flanges 22' similar to the flanges 14 on the sheet 13. If the sheet 22 is formed of resilient material, the label holder may be snapped over the edges of the back plate 7 just as in the case of the label holder shown in Figures 1, 2 and 3. In the case of non-resilient

material, the label holder can be positioned in any suitable manner, as by sliding it over the end of the back plate or bending the edges of the sheet 22 over the edges of the back plate.

5. A continuous U-shaped flange 23 is embossed from the sheet 22 to define a portion adapted to receive a label 24 and a transparent protecting member 25, as shown in Figure 6. The flange 23 is separated from the plane of the sheet 22 by 10 means of a U-shaped slot 26 which leaves a tab 27 integral with the sheet 22 that serves the same purpose as the tab 19.

While I have described two preferred embodiments of my invention in detail, it will be understood that the descriptions thereof are illustrative rather than restrictive, as many details may be modified or changed without departing from the spirit or scope of my invention. Accordingly, I do not desire to be restricted to 20 the exact construction described, except as limited by the appended claims.

I claim:

1. In a loose leaf binder, a back plate and a label holder, said label holder being provided 25 with flanges embracing opposite edges of said back plate.
2. In a loose leaf binder, a back plate, and a label holder provided with a pair of resilient flanges snapped over the edges of said back plate 30 to retain said label holder in position against said back plate.
3. In a loose leaf binder, a back plate, a member provided with resilient flanges embracing the edges of said back plate, and flanges embossed 35 from said member to receive a label thereunder.
4. In a loose leaf binder, a back plate, a label holder, flanges on opposite edges of said label holder embracing said back plate, a second plate on the opposite side of said flanges, and 40 means for clamping said second plate and said back plate together.
5. In a loose leaf binder, a back plate, a label holder provided with flanges embracing the edges of said back plate, a second plate, and 45 means integral with said back plate for clamping said back plate and said second plate together with said flanges therebetween.
6. In a loose leaf binder, a back plate, a decorative member covering a portion of the area of 50 said back plate and a transparent member provided with resilient flanges embracing the edges of said back plate to secure said transparent member over said decorative member.
7. In a loose leaf binder, a back member including two superimposed metal plates, and a 55 label holder fitting against the outer face of one

of said plates and having its edges clamped between said plates.

8. In a loose leaf binder, a plate having its edges curled to form barrel hinges, a back plate superimposed on said first mentioned plate and having its edges fitting within said curled portions of said first mentioned plate, and a label holder having its edges clamped between said plates. 80

9. A label holder including a transparent member provided with resilient flanges, a raised portion capable of receiving a label thereunder, a slot adjacent one edge of said raised portion, and a tab projecting from the edge of said transparent member adjacent said slot below the upper extremities of said raised portion to facilitate removal of a label positioned in said raised portion. 85

10. A label holder provided with an embossed portion, a slot adjacent one edge of said embossed portion, said slot being curved to provide a tab adapted to underlie a label inserted through said slot into the space covered by said embossed portion. 90

11. In a loose leaf binder, a back plate, and a transparent sheet member secured to said back plate by means of flanges embracing the edges of said back plate, a portion of said transparent sheet member being embossed, one edge of said embossed portion being provided with a slot curved to provide a tab depending below the upper extremities of said embossed portion. 95

12. In a loose leaf binder, a back plate, a decoratively figured sheet covering a portion of the area of said back plate, a transparent sheet member provided with resilient flanges embracing the edges of said back plate to secure said transparent sheet member over said decoratively figured sheet, an embossed portion on said transparent sheet member to form a space between said transparent sheet member and said decoratively figured sheet, a slot adjacent said embossed portion, and a tab integral with said transparent sheet member depending from the upper edge of said slot below the upper extremities of said embossed portion. 100

13. In a loose leaf binder, a back member including two superimposed metal plates, a decoratively figured sheet covering a portion of the exposed area of the outer plate, a transparent sheet member overlying said decoratively figured sheet and having its edges secured between said plates, said transparent sheet member having a raised portion capable of receiving a label thereunder. 105
